UNITED STATES PATENT OFFICE.

IRA DEMPSEY, OF DELAWARE, ARKANSAS.

FILE HOLDER.

Application filed October 18, 1923. Serial No. 669,369.

To all whom it may concern:

Be it known that I, IRA DEMPSEY, citizen of the United States, residing at Delaware, in the county of Logan and State of Arkansas, have invented certain new and useful Improvements in File Holders, of which the following is a specification.

This invention relates to file holders, and has particular reference to the provision of 10 a holder for files by means of which the latter may be more effectively and conveniently manipulated.

The primary object of the invention is to generally simplify and improve devices 15 of the above kind whereby the same may meet with all of the requirements for a successful commercial use.

Another object of the invention is to provide a file holder which is adjustable for 20 holding files of different sizes and lengths.

A further object is to provide an adjustable file holder which embraces the desired qualities of simplicity, durability, and efficiency in operation.

25 A still further object of the invention is to provide an adjustable file holder capable of being engaged with files of different sizes so as to provide a handle upon both ends of the file with the latter rigidly held between 30 said handle members.

Other objects will appear as the nature of the invention is better understood, and the same consists in the novel form, combination and arrangement of parts herein- 35 after more fully described, shown in the accompanying drawing, and claimed.

In the drawing, wherein like reference characters designate corresponding parts throughout the several views:

40 Figure 1 is an elevational view, showing a file holder constructed in accordance with the present invention operatively engaged with a file.

Figure 2 is a view similar to Figure 1, 45 looking at the opposite side of the device.

Figure 3 is a central longitudinal sectional view, taken substantially upon the line 3—3 of Figure 1.

Figure 4 is a transverse sectional view, 50 taken upon the line 4—4 of Figure 1, and

Figure 5 is an enlarged perspective view of the file engaging washer.

It is well known that when files are 55 grasped in the hands, the same are subjected to perspiration, and after some time rusting of the files takes place. Also, when the files

are not in use, they are laid upon benches and the like, in such position as to become clogged with dirt or other foreign matter, thus rendering their period of usefulness very short. In addition to this, when the ends of the file are grasped, a firm grip 60 cannot be readily had upon the same, and this results in less efficient operation of the file, as well as inconvenience to the user, particularly as the hands are disposed so as to cover a considerable portion of the operative part or body of the file.

It is accordingly an object of the present invention to provide a holder, by means of 70 which the undesirable features mentioned above are eliminated, and to this end I provide a file holder including a straight rod 5, having the ends thereof threaded, and extended into longitudinal central bores 6, 75 provided in similar handle members 7. The handle members 7 are preferably in the form of relatively short cylinders constructed of wood or the like, and are provided intermediate their ends with transverse recesses 80 8, one recess being provided for each handle, and each recess intersecting the bore 6 of the handle. Arranged within the recesses 8 are nuts 9, through which the threaded ends of the rod 5 are screwed, and due to the 85 angular formation of the recesses 8, said nuts are effectively held against turning movement relative to the handle members 7. In other words, the handle members, when turned, will cause the nuts 9 to be 90 threaded onto the ends of the rod 5, and by providing the rod 5 of proper length, a file holder may be provided, which may be adjusted within a required range for holding files of different sizes.

95 Disposed against the inner end of one of the handle members 7 and upon the rod 5 is a washer 10 of relatively thick form, that is provided at one side of its central opening 11 with a transverse groove 12 for seating 100 reception of the blunt end of a file 13 of the usual and well known form. The other handle member 7 is provided with a longitudinal internal groove as at 14 for snug reception of the usual pointed or narrow end 105 portion of the file 13, as shown clearly in Figures 1 and 3.

In use, the handle members 7 are separated by turning the same in the proper direction relative to the rod 5, in order to 110 allow the pointed end of the file 13 to be inserted into the groove 14 of one of the

handle members. The washer 10 is then slid toward the blunt end of the file until said end is seated within the groove 12 of the said washer, whereupon the handle member 7 adjacent the washer is threaded onto the adjacent end of the rod 5, until the inner end of the last mentioned handle member engages the outer side of said washer 10 forcing the same into close contact with the blunt end of the file, and forcing the pointed end of the file snugly into the groove 14. The device is then ready for use, and it is apparent that the file may be readily removed by a reversal of this operation, if it is desired to use the reverse side of the file or use a new one. Also, as an effective grip may be had upon the handle member 7 at both ends of the file without covering any operative portion of the latter, it is apparent that the file may be used with great efficiency and without danger of rusting due to perspiration getting on the file from the user's hands. Also, when the device is not in use, it may be freely laid upon a bench or the like with the handle members 7 holding the file in position out of contact with the surface of the bench and thus out of contact with dirt or dust thereof.

From the above it will be seen that I have provided a simple, durable, and efficient form of file holder, which embraces a comparatively few number of parts capable of being easily and expeditiously manipulated.

Minor changes may be made without departing from the spirit and scope of the invention as claimed.

What I claim as new is:

1. In a file holder, a pair of similar handle members provided with central longitudinal bores and having transverse recesses intersecting said bores, nuts arranged within the recesses and held therein against rotation relative to the handle members, a rod having threaded ends respectively threaded through the nuts and extending through the bores of the handle members whereby the latter may be adjusted toward and away from each other longitudinally of the rod, one of said handle members having a longitudinal internal groove for seating reception of the pointed end of a file, and a washer arranged upon the rod adjacent the inner end of the other handle member and provided with a transverse groove for seating reception of the blunt end of the file. 55

2. A file holder comprising a pair of cylindrical handle members provided with longitudinal central bores extending entirely therethrough and having transverse recesses intersecting said bores, nuts within the recesses and held thereby against rotation relative to the handle members, a rod having threaded ends projecting the bores of the handles and threaded through the nut, and means carried by the rod adjacent the inner end of one of the handle members for retaining engagement with one end of a file, and the other handle member being provided with means whereby the same may retainingly engage the other end of a file. 70

In testimony whereof I affix my signature.

IRVING DEMPSEY.
